UNITED STATES PATENT OFFICE.

CLYDE W. BLAKESLEE, OF CHICAGO, ILLINOIS, ASSIGNOR OF TWENTY-FOUR AND ONE HALF ONE-HUNDREDTHS TO IRA J. McDOWELL AND TWENTY-FOUR AND ONE-HALF ONE-HUNDREDTHS TO WESTLY H. WESTBROOK, BOTH OF CHICAGO, ILLINOIS.

STREET-TRAFFIC SIGNAL.

1,254,305.

Specification of Letters Patent. Patented Jan. 22, 1918.

Application filed January 24, 1916. Serial No. 73,917.

To all whom it may concern:

Be it known that I, CLYDE W. BLAKESLEE, a citizen of the United States, and a resident of the city of Chicago, county of Cook, 5 and State of Illinois, have invented certain new and useful Improvements in Street-Traffic Signals, of which the following is a specification.

My invention relates to improvements in 10 street traffic signals, and has for its object the provision of an improved manually operable construction for controlling the traffic at street corners in large cities.

The invention consists in the combinations 15 and arrangements of parts hereinafter described and claimed.

The invention will be best understood by reference to the accompanying drawings forming a part of this specification, and in 20 which,

Figure 1 is an elevation shown partially in section of a signal post employed in the construction,

Fig. 2, an enlarged section taken on line 25 2—2 of Fig. 1,

Fig. 3, an enlarged section taken through a watch tower employed in the construction,

Fig. 4, a horizontal section taken through 30 a conduit leading from the watch tower to the signal post and located under the street,

Fig. 5, a view of the watch tower,

Fig. 6, an elevation of the upper portion of the signal post,

Fig. 7, a view similar to Fig. 6 but shown 35 partially in section,

Fig. 8, a top plan view of the signal post,

Fig. 9, an enlarged detail view of a signal gong employed in the construction, and

Fig. 10, a horizontal section illustrating 40 the signal gong clapper.

The preferred form of construction, as illustrated in the drawings, comprises a hollow metallic post 11 which is preferably set at the center of a street crossing and has a 45 hollow shaft 12 extending therethrough and operating therein. A conduit 13 is buried in the street leading from under post 11 to a corner of a sidewalk of the crossing. A segmental pinion 14 is mounted in the conduit 13 on the lower end of shaft 12 and meshes with a segmental gear 15 also mounted in said conduit and connected by wires or cables 16 with a cross arm 17 secured to the lower end of a hollow vertical shaft 18

located at the sidewalk corner. The shaft 55 18 extends upwardly through a hollow supporting post 19 mounted at the sidewalk corner and carrying a watch tower 20 at its top. At its upper end shaft 18 is provided with a segmental bevel gear 21 meshing with 60 a segmental bevel gear 22 operable by means of a handle lever 23 by an operator in said watch tower. The arrangement is such, as will be observed, that the operator in the watch tower 20, by manipulating lever 23, 65 may readily oscillate shaft 12 in signal post 11 through an angle of ninety degrees. A hollow signal cross-arm 24 is secured to the upper end of shaft 12 above post 11 and is provided on each side with translucent stop 70 signs, an electric light bulb 25 being located in each of said arms. Another electric light 26 is mounted centrally on arms 24 to serve as a general illumination when desired. A depending sign member 27 in the form of a 75 sleeve is mounted to operate with arms 24 and is also provided with a translucent sign as indicated in Fig. 6, co-operating with the signs on arm 24, said depending sign member being provided to facilitate view by 80 people situated in low covered vehicles. Electric light bulbs 28 are arranged in depending sign 27 to illuminate the interior thereof at night. The electric lights 25, 26 and 28 are connected by means of wires 29, 85 with a switch 30 located in the watch tower 20 and connected with electric supply wires 30' by means of which said lights may be controlled by the operator.

A cam plate 31 is secured to the upper end 90 of shaft 12 immediately below arm 24 and is provided with depending cam lugs 32 and 33 there being two of the lugs 33 set on a circle with the axis of shaft 12 as a center slightly within the corresponding circle for 95 lug 32. A spring held bell clapper 34 is provided with two upstanding oppositely acting spring held dogs 35 and 36, the dog 35 being set in the path of cam lug 32 and the dog 36 being set in the path of cam lug 100 33, the arrangement being such that as shaft 12 is rotated in one direction the dog 35 will be operatively engaged by the cam lug 32 and the clapper 34 operated to strike the gong 37 a single blow, the dog 36 passing 105 idly under cam lugs 33 during this operation. Upon reverse oscillation of shaft 12, the dog 36 operatively engages the cam lugs

33 to strike two blows on the gong 37, dog 35 idly passing cam lug 32, as will be readily understood. By this arrangement, it will be observed that upon each oscillation of the 5 signal arm 24 one stroke of the gong will be sounded upon the oscillation in one direction, and two strokes of the gong will be sounded upon the oscillation in the other direction.

10 An electric clapper 38 is mounted in a casing 39 containing suitable electrical mechanism for operating the same to sound the gong 37 continuously and uniformly. The apparatus in casing 39 is operatively connected with electric wires 40 which pass downwardly through shaft 12, thence through conduit 13 upwardly through shaft 18, connected with the switch 41 in the watchman's tower. By this arrangement in case of fire, 15 the operator may sound a signal which will notify the traffic that the fire apparatus is approaching and that the street must be 20 clear.

In use the signal post 11 is set at the 25 center of a street crossing and the signal arm 24 and depending signal 27 set on the shaft 12 to point longitudinally along one street and at right angles to the other, thus indicating that said one street is open to traffic 30 and the other closed. When the operator desires to alter the trend of traffic he oscillates shaft 12 to throw the signal arm through an angle of ninety degrees and thus to extend along the other street and across 35 the first street. At one movement of arm 24 a single audible signal will be given by gong 37 and at the other movement of said arm two audible signals will be given by said gong, as explained above to further assist 40 in control of the traffic. In case of fire a general alarm may be given for clearing the street along which the fire apparatus is approaching and signal arm 24 be manipulated to indicate said street.

45 While I have illustrated and described the preferred form of construction for carrying my invention into effect, this is capable of variation and modification without departing from the spirit of the invention. 50 I, therefore, do not wish to be limited to

the precise details of construction set forth, but desire to avail myself of such variations and modifications as come within the scope of the appended claims.

Having described my invention what I 55 claim as new and desire to secure by Letters Patent is:

1. A street traffic signal for street crossings comprising a hollow post; a shaft operating in said post; a signal mounted at 60 the top of said post on said shaft; a gong; a clapper for said gong; means on said shaft for operating said clapper different numbers of times upon oscillating said shaft in different directions; and means for operating 65 said shaft, substantially as described.

2. A street traffic signal for street crossings comprising a hollow post, a shaft arranged in said post, a signal on the upper end of said shaft, a gong, a clapper for said 70 gong, a pair of oppositely operating dogs on said clapper, means rotatable with said signal for operatively engaging one of said dogs when the shaft is rotated in one direction to actuate the clapper a given number 75 of times and for operatively engaging the other dog when the shaft is rotated in the opposite direction to operate the clapper a different number of times, and means for oscillating said shaft, substantially as de- 80 scribed.

3. In a device of the class described the hollow post, a shaft in said post, a signal mounted on the upper end of said shaft and rotatable therewith, a gong mounted upon 85 said post, a clapper for said gong, a pair of oppositely operating dogs on said clapper, a single lug on said signal adapted to operatively engage one of said dogs and a pair of lugs on said signal adapted to op- 90 eratively engage the other dog, and means for oscillating said shaft.

In testimony whereof I have signed my name to this specification in the presence of two subscribing witnesses.

CLYDE W. BLAKESLEE.
